UNITED STATES PATENT OFFICE

151,781

DESIGN FOR A DISPLAY STAND OR SIMILAR ARTICLE

Laurence B. Morrison, Canajoharie, N. Y., assignor to Beech-Nut Packing Company, Canajoharie, N. Y., a corporation of New York

Application March 25, 1947, Serial No. 137,869

Term of patent 14 years

(Cl. D80—9)

To all whom it may concern:

Be it known that I, Laurence B. Morrison, a citizen of the United States, residing at Canajoharie, county of Montgomery, State of New York, have invented a new, original, and ornamental Design for a Display Stand or Similar Article, of which the following is a specification, reference being had to the accompanying drawing, forming part thereof.

Figure 1 is a view in perspective of a display stand or similar article, showing my new design; and

Fig. 2 is a plan view thereof.

I claim:

The ornamental design for a display stand or similar article, as shown.

LAURENCE B. MORRISON.
